UNITED STATES PATENT OFFICE

142,457

DESIGN FOR AN AUTOMOBILE

Edward C. Wells, Donald J. Euler, and Norbert A. Collins, near Seattle, Wash., assignors to Boeing Aircraft Company, Seattle, Wash., a corporation of Washington

Application August 9, 1944, Serial No. 114,797

Term of patent 14 years

(Cl. D14—3)

To all whom it may concern:

Be it known that we, Edward C. Wells, Donald J. Euler, and Norbert A. Collins, citizens of the United States of America, residing at or near Seattle, in the county of King and State of Washington, have invented a new, original, and ornamental Design for an Automobile, of which the following is a specification, reference being had to the accompanying drawings, forming part thereof.

Figure 4 is a fragmentary elevational view of a portion thereof taken on line 4—4 of Figure 3, illustrating the design as it appears with the front passenger's seat in rearward position.

The interior of the automobile shown in full lines in the drawings is the dominant feature of our new design.

We claim:

The ornamental design for an automobile, substantially as shown and described.
